INVENTOR

BY Victor J. Evans

ATTORNEY

UNITED STATES PATENT OFFICE.

FRANK JONES WIGREN, OF NEW YORK, N. Y.

TOOL.

Application filed March 10, 1926. Serial No. 93,676.

This invention relates to improvements in tools and has particular reference to a novel construction of tool holder for interchangeably receiving different tool elements.

5 The principal object of the invention resides in a tool holder adapted to serve as a handle for a plurality of different tool elements, whereby a complete set of tools such as different size chisels and the like may be carried in a carpenter's kit or tool chest and respectively fitted into the holder when the selected tool is desired for use. This arrangement keeps a set of tools compact and reduces the cost of manufacture as the tool 10 elements are constructed without the usual handles.

Another object resides in a tool holder or handle for use in connection with chisels and other tools which are adapted to receive a blow from a hammer or mallet, in which provision is made for preventing the handle from splitting due to excessive use, and in which the shock due to the impact is absorbed to prevent the tool or instrument 15 from being jarred while in the hand of the user.

With these and other objects in view, the invention resides in certain novel construction and combination and arrangement of parts, the essential features of which are hereinafter fully described, are particularly pointed out in the appended claims, and are illustrated in the accompanying drawing, in which:

20 Figure 1 is a vertical longitudinal sectional view of my improved tool.

Figure 2 is a horizontal sectional view on the line 2—2 of Figure 1.

Figure 3 is a collective side elevation of 25 the parts in a separated condition.

Referring more particularly to the drawing, the reference numeral 10 designates a member in the nature of a sleeve or ferrule which is provided with a socket 11 in one 30 end thereof and a socket 12 in the other end. A threaded bore 13 connects the two sockets for a purpose to be presently described.

Fitted within the socket 12 is a reduced 35 shank 14 of a tool element 15, which element is shown as a chisel. On the free end of the reduced shank 14, there is provided a threaded stud 16 which co-acts with the walls of the threaded opening 13 for holding the tool element locked in position. When 40 the tool element has been seated, the same

is held firm and may be readily removed by rotating the element 15 in a direction opposite to that for attaching the element to the member.

80

A handle member 17 is provided with a reduced portion 18, which is inserted in the socket 11. The bottom walls of the socket 11 are inclined toward the center and interposed between said walls and the end of the portion 18, is a cushion member 19 in the nature of a rubber disk. A rubber ring or cushion member 20 encircles the reduced portion 18 and is interposed between the end of the member 10 and the shoulder 21 on the handle member formed by reason of the reduced portion 19. The handle is securely anchored within the socket by suitable screws or the like fastening elements 22. It might be mentioned that the handle is adapted to be constructed of a relatively tough wood such as hickory and the outer end of the same is reduced to receive a metallic band 23. This band is adapted to strengthen the outer end of the handle and to prevent 50 the same from being worn down through continuous contact by a mallet or hammer.

75

From the foregoing description, it will be seen that the tool elements 15 may be of various sizes, that is, the size of the cutting edges may vary as it is the usual practice for a carpenter's kit to contain a set of different size chisels. Any of these chisels may be attached to the member 10 in the manner already described as they are needed 55 for use, and when not in use they may be kept in suitable pockets provided in a kit bag or a tool chest. It will be further appreciated that when a blow is imparted to the end of the handle 17, the shock will be 60 absorbed by the cushion members 19 and 20, which prevents the tool from jarring when being held in position against a piece of work. This permits a carpenter or one skilled in the art to use the tool to its maximum efficiency. It might be mentioned that the ring 23 serves to prevent the handle member from splitting and so prolongs the 65 life of the handle.

100

While I have described what I deem to be the most desirable embodiment of my invention, it is obvious that many of the details may be varied without in any way departing from the spirit of my invention, and I therefore do not limit myself to the exact 105 details of construction herein set forth nor to anything less than the whole of my in-

110

vention, limited only by the appended claims.

What is claimed as new is:—

1. A tool comprising a member having oppositely disposed sockets therein, a tool element having a reduced shank fitted in one of said sockets, co-acting means between said shank and said member for locking said tool element therein, a handle having a reduced portion for insertion in the other of said sockets, and cushion members interposed between said handle member and said member.
2. A tool comprising a member having op-

positely disposed sockets therein, a threaded bore connecting said sockets and adapted to receive the threaded end of a tool element for locking engagement therewith, and a handle member having a reduced end fitted in one of said sockets, and cushion members respectively interposed between the end wall of said socket and said reduced end, and between the end of said member and a shoulder on said handle member.

In testimony whereof I have affixed my signature.

FRANK JONES WIGREN.
